UNITED STATES PATENT OFFICE.

LEE B. GREEN, OF LAKWOOD, OHIO, ASSIGNOR TO THE BORDEN COMPANY, OF WARREN, OHIO, A CORPORATION OF OHIO.

VISE.

Application filed April 13, 1926. Serial No. 101,644.

This invention relates to vises and more particularly pipe vises.

It is one of the objects of the present invention to provide a vise that is adapted to be quickly opened and closed and for clamping pipes of various sizes.

Another object of the invention is to provide a vise that is self-opening for the purpose of releasing the pipe.

Other objects of the invention are to provide an improved construction that will be easy to manufacture, at a low cost, and that will be durable and capable of withstanding the rough usage to which such devices are subjected in service.

Other objects of the invention and the features of novelty will be apparent from the following description taken in connection with the accompanying drawings, of which:

Fig. 1 is a side elevation of a vise embodying my invention, certain parts being broken away and other parts being shown in section;

Fig. 2 is a plan view thereof;

Fig. 3 is a front elevation; and

Fig. 4 is a section on the line 4—4 of Fig. 1.

Referring to the drawings, 10 and 11 indicate side plates of a frame which are spaced apart and have bottom flanges 12 that are welded or riveted, or otherwise suitably secured on a base plate 13. Stationary jaws 14 and 15 are secured on the side plates 10 and 11, respectively, by means of the bolt 16, there being a tubular spacer 17, on this bolt, between the plates 10 and 11.

The side plates 10 and 11 are provided with grooves or ways 18, on their inner faces in which the keys 19, on the movable jaw member 20, slide. One of the keys 19 carries a dowel pin 21 which projects into a groove 22, the upper end of this groove stopping a short distance from the upper end of the side plate 10, so that the engagement of the pin 21, with the end of the groove, serves to limit the upward movement of the jaw member 20. A bolt 23 extends across the space between the side plates 10 and 11, adjacent the bottom thereof, and carries a spring 24, which engages with the lower end of the movable jaw 20 for the purpose of automatically lifting the latter to the upper limit of its movement, when it is released.

On the rear side of the movable jaw member 20, there is a series of teeth or serrations 25 which are adapted to be engaged by corresponding teeth 26 on the member 27, which is

arranged to slide between the side plates 10 and 11 and is carried by the lower end of the screw 28. There is a circumferential groove 29, in the screw 28, and a dowel pin 30, carried by the member 27, engages this groove 60 so as to secure these parts together by a connection that permits the screw to be rotated independently of the member 27. Between the lower end of the screw 28 and the bottom of the socket 31, in the member 27, there is a ball 32 which serves as a thrust bearing. The upper end of the screw 28 has a head 33 in which a handle 34 is secured by means of the dowel pin 35.

A nut 36 is arranged between the side plates 10 and 11 and provided with trunnions 37, on its opposite sides, which engage suitable openings therefor, in the side plates 10 and 11, so that the nut is adapted to rock relative to the side plates, although held in a substantially permanent relation thereto. The screw 28 engages the nut 36 so that the screw moves longitudinally through the nut when rotated, such longitudinal movement also actuating the member 27. A bolt 38 connects the side plates 10 and 11 together, at the rear of the vise, and carries a suitable spring 39 which engages the member 27 and normally holds the teeth 26 in engagement with the teeth 25. The side plates 10 and 11 are further connected together by the bolt 39' and spacers are provided on the bolts 38 and 39', against which the side plates are clamped.

In Fig. 1, there is a pipe P, between the stationary and movable jaws of the vise, and the pipe may be securely clamped between these jaws by turning the screw 28 so as to lower the member 27, which carries the movable jaw 20 with it, on account of the engagement of the teeth 25 and 26. When it is desired to release the pipe, the screw 28 is slightly rotated in the opposite direction, to release the pressure of the teeth 26 on the teeth 25 and the screw and nut are then rocked on the trunnions 37 to withdraw the teeth 26 from engagement with the teeth 25. This permits the spring 24 to lift the jaw 20 to its upper position, thereby releasing the pipe and opening the jaws for the reception of another pipe. So long as the member 27 is held away from the movable jaw 20, this jaw may be freely moved up and down but when the operator releases the screw 28, or its handle 34, which he will ordinarily use for mov-

ing the screw, the spring 39 will move the member 27 over against the movable jaw 20 and effect the engagement of the teeth 25 and 26. The movable jaw 20 may then be depressed against the pipe P, the teeth 25 and 26 being so shaped, as shown in Fig. 1, to permit the teeth 25 to slide over the teeth 26. The screw 28 is then rotated to further depress the jaw 20 to securely clamp the pipe.

From the foregoing it will be seen that I have provided a comparatively simple form of construction that will permit the jaw 20 to be quickly moved either to its closed or open position, by rocking the screw 28 and the nut 36 on the trunnions 37 to disengage the teeth 25 and 26.

Having thus described my invention, what I claim is:

1. In vises, the combination of a stationary jaw, a sliding jaw, a member movable with said sliding jaw and independently thereof, said sliding jaw and said member having interlocking parts whereby the sliding jaw may be moved toward the stationary jaw by said member, a nut held in substantially fixed relation to said stationary jaw, and a screw in said nut and rotatably engaging said member to move the latter.

2. In vises, the combination of a stationary jaw, a sliding jaw, a member movable with said sliding jaw and independently thereof, said sliding jaw and said member having interlocking parts whereby the sliding jaw may be moved toward the stationary jaw by said member, a pivoted nut held in substantially fixed relation to said stationary jaw, and a screw in said nut rotatably engaging said member to move the latter, and said screw being adapted to swing about the pivot of said nut to disengage said member from the sliding jaw.

3. In vises, the combination of a stationary jaw, a sliding jaw, a member movable with said sliding jaw and independently thereof, said sliding jaw and said member having interlocking parts whereby the sliding jaw may be moved toward the stationary jaw by said member, a pivoted nut held in substantially fixed relation to said stationary jaw, a screw

in said nut rotatably engaging said member to move the latter, said screw being adapted to swing about the pivot of said nut to disengage said member from said sliding jaw, and means for automatically moving the sliding jaw away from the stationary jaw when said member is disengaged from the sliding jaw.

4. In vises, the combination of a frame, a pair of jaws one of which is movable and the other stationary, a nut pivoted on said frame, a screw engaging said nut, a member carried by said screw and adjustably connected with said movable jaw and also movable independently thereof about the nut pivot, said movable jaw being freely movable toward or away from the stationary jaw when disengaged from said member, means for normally holding said member in engagement with the movable jaw, and means for automatically moving the movable jaw away from the stationary jaw.

5. In vises, the combination of a frame, a stationary jaw on said frame, a jaw movable on said frame toward and away from the stationary jaw and having a series of teeth on one side, a screw mounted for swinging movement on said frame, a member actuated by said screw and having teeth adapted to engage the teeth on said movable jaw, and means for yieldingly holding said teeth in engagement.

6. In vises, the combination of a frame, a stationary jaw on said frame, a jaw movable on said frame toward and away from the stationary jaw and having a series of teeth on one side, a nut pivotally mounted on said frame, a screw carried by said nut and movable longitudinally therethrough, a member slideable in said frame and held against rotation but carried by said screw and having teeth adapted to engage the teeth on said movable jaw, said screw being rotatable in said member and the latter partaking of the longitudinal and rocking movements of the screw.

In testimony whereof, I hereunto affix my signature.

LEE B. GREEN.
